UNITED STATES PATENT OFFICE

JOSEPH DE ROSE, OF PHILADELPHIA, PENNSYLVANIA

WATER-CLOSET

Application filed November 3, 1928. Serial No. 317,075.

This invention relates to water closets and more particularly to the type having a flush-water tank forming part of the bowl and valve mechanism which, when the closet seat is relieved of pressure, ensures thorough flushing of all parts of the bowl.

The primary object of my present improvements is to provide an anti-freeze water closet, of the above noted type; or, in other words, I aim to furnish a water closet adapted for "outside" installation without liability of its becoming inoperative in cold and frosty weather.

Another object is the provision of a simple and efficient distant service-supply control and a local flush control with means co-ordinating the same for alternate opening and closing.

A further object is to provide an automatic water closet which is thoroughly sanitary and does not involve provision of a "pit" when installed out of doors.

Other objects embrace the novel details of construction, combinations and arrangements of parts, hereinafter fully described, shown by the accompanying sheet of drawings, and specifically defined in the appended claims.

To the foregoing ends my invention essentially consists in locating the service-supply control below normal freezing level and a direct-connected local flush control, with novel operating means co-ordinating actuation thereof by pressure applied to—and relief of pressure from—the closet seat.

In the drawings:—

Fig. I is a vertical sectional view of a water closet embodying my present improvements.

Fig. II is a relatively enlarged sectional view showing the service-supply and flush controlling mechanism, part being broken out for convenience in illustration; and,

Fig. III is a further enlarged sectional detail taken approximately on the plane designated III—III in Fig. II.

Referring more in detail to the drawings, the numeral 5 generally designates a water closet bowl of conventional type, and more particularly adapted for outside use; that is to say it is devoid of a water seal concavity in its lower portion. This bowl 5 is provided

with a discharge outlet 6 for appropriate connection at 7 to the soil or sewer pipe 8, as well as a basal flange 9 whereby it is secured to the floor 10 by fastening means 11, with interposition of a suitable sealing gasket 12. Formed integral with the bowl 5 about its top is an annular flush water reservoir 13, having communication—through a valve controlled port 14 in a separating diaphragm 15—into the subjacent distributing ring or channel 16 which discharges into said bowl by way of perforations 17 in the usual way.

For the purpose of controlling the filling of, and flushing from, the reservoir 13, I make use of the novel valve and actuating mechanism therefor, now to be described. Fitted to the upper end of the service pipe 18, by means of an appropriate union coupler 19, is a valve casing 20 of tubular formation that is provided interiorly with radial ribs 21 which determine flow passages 22, while affording guidance for a plunger type valve 23 adapted to co-operate with a concentric seat 24 in said casing, in controlling supply and cut-off by way of the service pipe 18. It is to be particularly observed that the valve casing 20 is located well below the ground or floor level 10; or, in such a position as is well below normal ground freezing level in the vicinity of the closet installation. Furthermore, it is noteworthy that I provide the valve casing 20 with a lateral outlet 25 communicating by a downwardly inclined tubular connection 26 and coupler nipple 27 into the soil or sewer pipe 8, for a purpose later on explained.

Conveniently screw-threaded and sealed into the upper end of the valve casing 20 is a vertically directed pipe 28 which passes through the floor 10, and is furnished at its upper end with a union coupler 29 whereby it is removably connected to the lower end of a plunger casing 30 disposed co-axial with the port 14 in the diaphragm 15, aforementioned. This plunger casing 30 is formed with an integral spider flange 31—intermediate its ends—affording apertures 32 therethrough, and a concentric groove 33 for reception of a rubber—or other appropriate material—annulus 34; while it is clamped

relative to the diaphragm 15 and distributor channel 16, in a lateral offset 16' of the latter, by means of upper and lower sealing gaskets 35, 36 respectively, and a lock nut or nuts 37, in an obvious manner.

Slidably fitting the upper portion of the plunger casing 30 is a tubular cap 38 having an invert dished flange 39 for co-operation with the annulus 34, as hereafter set forth, and a co-axial integral—or attached—stem 40 reciprocable axially through a stuffing box 41, forming part of a cupped attachment 42 sealed in an aperture 13' of the top wall of the flush water reservoir 13, through the medium of a compressible gasket 43 and conventional attaching means 44. The tubular cap 38 is normally maintained in the elevated position shown under the influence of a compression spring 45 housed therein between the closed-in upper end 46 thereof and the top edge of the plunger casing 30; and, said cap is provided with a series of elongated orifices 47 about its tubular wall for a purpose hereafter explained. In addition to the function just mentioned of the spring 45, it also serves to support the weight of the closet seat 48 and to normally hold the same slightly elevated relative to the closet bowl 5, as illustrated; said seat being hinged at 49 to a conventional device 50, sealed in an offset 51 of the aforesaid flush-water reservoir 13.

Provided within the upper portion of the plunger casing 30 are a series of radial ribs 52, similar in character and purpose to the ribs 21 hereinbefore described, that serve to afford guidance for a piston member 53 formed on—or attached to—the upper end of an actuator or connecting rod 54, securely connected to the plunger valve 23 which controls the service connection 18. Operative connection between the piston member 53 and the tubular cap 38 is afforded by motion translating devices 55, connected at 56—with freedom for limited longitudinal movement—between spaced ears 57 on the dished flange 39, and which pass through appropriate slots and orifices 58, 59, respectively in the body portion of said cap 38 and the upper end of the plunger casing 30. It is also to be noted that the free ends of the motion translating devices 55 operatively engage in a comparatively deep groove 60 in the piston member 53; while they are enlarged or fashioned substantially spherical at 61 where they engage in the orifices 59, whereby they are afforded fulcrum bearing thereat.

The operation of my improved anti-freeze closet is briefly as follows:—

As the hinged seat 48 is depressed by a user of the closet, the resistance of the compression spring 45 is overcome, with the result that the stem 40 and tubular cap 38 are moved downward until the dished flange 39 engages and seats on the annulus 34, thereby

closing communication between the flush-water reservoir 13 and the distributor ring or channel 16. Concurrently with the movement just described the motion-translating devices 55 are rocked upon their fulcrum 70 bearings 61, thus elevating the piston member 53, and, through the connecting rod 54 lifting the plunger valve 23 from its seat 24, whereby the service connection 18 is opened to permit filling of the reservoir 13 75 with flushing water flowing upwardly through the pipe 28, plunger casing 30, and voiding out through the elongated cap orifices 47 past the piston member 53. With closure of the port 14 and apertures 32 by 80 the dished cap flange 39, a certain amount of air will be trapped in the reservoir 13 and compressed by the inrushing water from service 18, the flow of said water continuing until an equalization of pressure obtains. 85 When the seat 48 is released incident to the user rising therefrom, the compression spring 45 instantly functions to elevate the tubular cap 38 with concurrent raising of the seat by the stem 40 to normal inactive 90 location, whereby the piston member 53 is simultaneously lowered—by the devices 55—and the plunger valve 23, seated, thus shutting-off further flow from the service 95 connection 18. Incident to the movements just set forth, the water stored in the reservoir 13 is expelled via the apertures 32, and port 14, into the distributor channel 16 for 100 forced dissipation through the perforations 17 about the wall of the closet bowl 5, thereby expediting flushing the same, such operation being expedited under pressure of the air trapped as described above in connection with the reservoir filling period. Furthermore, as a result of the action just set forth, 105 a quantity of the water contained in the casing 30, and pipe 28, will be siphoned out through the orifices 47 thereby augmenting the flushing charge or until an equalization of pressure again obtains; while any remaining in said parts is promptly drained-off via the connection 26, into the soil or sewer pipe 8; thereby freeing the entire connections above the valve 23 of all water that might collect or otherwise be retained above the 110 freezing level in cold weather.

From the foregoing it will be apparent that I have provided an improved water closet that is entirely automatic and particularly adapted for out of doors use—while not so restricted, the same being simple in construction and devoid of any parts liable to become deranged or get out of order under constant use or careless misuse.

Having thus described my invention, what 115 I claim is:—

1. The combination with a water closet embodying a flush-water reservoir about its top and a yieldingly supported seat, of a remote valve located well below normal ground. 120

freezing level and controlling supply of flush-water to said reservoir, and an aligned opposedly movable local valve governing discharge of water from the reservoir for flushing purposes, both of said valves being actuated by the closet seat.

2. The combination with a water closet embodying a flush-water reservoir about its top and a yieldingly supported seat, of a remote valve controlling supply of flush-water to the reservoir, and an aligned opposedly movable operatively-connected local valve concurrently actuated by the closet seat in governing discharge of water from the reservoir for flushing purposes.

3. The combination with a closet bowl embodying a flush-water reservoir about its top and a yieldingly supported seat, of a local valve within said reservoir, an aligned distant valve interposed in the service supply, and means operatively co-ordinating said valves for concurrent differential actuation by the closet seat to effect flushing of the bowl aforesaid.

4. The combination with a closet bowl embodying a flush-water reservoir about its top and a yieldingly supported seat, of a local valve within said reservoir, an aligned distant valve interposed in the service supply, means operatively co-ordinating said valves for concurrent differential actuation by the closet seat to effect flushing of the bowl aforesaid, and means affording drainage intermediate said valves when the service supply is shut-off.

5. The combination with a closet bowl embodying a flush-water reservoir about its top and a yieldingly supported seat, of a local valve in the reservoir governing discharge of flush-water therefrom, an aligned opposedly-acting distant valve controlling supply of flush water to the reservoir, and means operatively connecting said valves for concurrent differential actuation by the seat to effect flushing of the bowl aforesaid.

6. The combination with a water closet embodying a flush-water reservoir about its top and a yieldingly supported seat, of a local valve interposed in the reservoir to govern discharge of flush-water therefrom, said valve comprising a tubular casing having an apertured flange affording outlet from the reservoir with provision of an annular seat, a co-operative axially movable valve member spring-influenced to normally support the closet seat, means in the tubular casing connecting with an aligned distant valve controlling supply of flush-water to the reservoir, and mechanism co-ordinating the axially movable valve member with the distant valve for concurrent differential actuation by the closet seat.

7. The combination with a water closet embodying a flush-water reservoir about its top and a yieldingly supported seat, of a local

valve interposed in the reservoir to govern discharge of flush-water therefrom, said valve comprising a tubular casing having an apertured flange affording outlet from the reservoir with provision of an annular seat, a co-operative axially-movable tubular cap on said casing with a stem spring-influenced to normally support the closet seat, means in the tubular casing connecting with an aligned distant valve controlling supply of flush-water to the reservoir, and mechanism co-ordinating the axially movable cap valve with the distant valve for concurrent differential actuation by the closet seat.

8. The combination with a water closet embodying a flush-water reservoir about its top and a yieldingly supported seat, of a local valve interposed in the reservoir to govern discharge of flush-water therefrom, said valve comprising a tubular casing having an apertured flange affording outlet from the reservoir with provision of an annular seat, a co-operative tubular cap on said casing with a stem spring-influenced to normally support the closet seat, a piston member fitting the tubular casing with provision of longitudinal flow passages thereabout, means directly connecting said piston to a distant valve controlling supply of flush-water to the reservoir, and mechanism co-ordinating the axially movable cap valve with the piston member and distant valve for concurrent actuation by the closet seat.

9. The combination with a water closet embodying a flush-water reservoir about its top and a yieldingly supported seat, of an axially movable local valve interposed in the reservoir to govern discharge of flush-water therefrom, said valve comprising a tubular casing having an apertured flange affording outlet from the reservoir with provision of an annular seat, a tubular cap slidably fitting said casing with a stem spring-influenced to normally support the closet seat and a dished valve member co-operative with the annular seat, a piston fitting the tubular casing with provision of longitudinal flow passages thereabout, a distant valve interposed in the service connection for controlling supply of flush-water to the reservoir, said distant valve comprising a casing having internal radial ribs and a concentric seat with which a plunger valve co-operates, and mechanism co-ordinating the axially movable valve with the distant valve for concurrent actuation by the closet seat.

10. The combination with a closet bowl embodying a flush-water reservoir about its top and a yieldingly supported seat, of an axially movable local valve interposed in the reservoir to govern discharge of flush-water therefrom, said valve comprising a tubular casing having an apertured flange affording outlet from the reservoir with provision of an annular seat, a tubular cap freely fitting the

- upper end of said casing with a stem spring-influenced to normally support the closet seat and a dished valve flange co-operative with the annular seat, a piston fitting the tubular casing with provision of longitudinal flow passages thereabout, a distant valve interposed in the service connection for controlling supply of flush-water to the reservoir, said distant valve comprising a casing
- 5 having internal radial ribs with a subjacent concentric seat, a plunger valve slidably fitting said distant valve casing and directly connected to the local valve, and motion transmitting means afforded fulcrum bearing in the local valve casing co-ordinating the tubular cap with the piston member aforesaid, whereby the local and distant valves are concurrently actuated by the closet seat to effect flushing of the bowl aforesaid.
- 10 11. The combination with a closet bowl embodying a flush-water reservoir about its top and a yieldingly supported seat, of a local valve interposed in the reservoir to govern discharge of flush-water therefrom, said
- 15 valve comprising a tubular casing having an apertured flange affording outlet from the reservoir with provision of an annular seat, a tubular cap freely fitting the upper end of said casing with a stem spring-influenced to
- 20 normally support the closet seat and an integral dished valve flange adapted to engage the annular seat, a piston fitting the tubular casing with provision of longitudinal flow passages thereabout, a direct-connected distant valve interposed in the service connection for controlling supply of flush-water to the reservoir, said distant valve comprising a casing having internal radial ribs with a subjacent concentric seat, a plunger valve
- 25 fitting said last mentioned casing and co-operative with the seat therein, motion transmitting devices afforded fulcrum bearing in the local valve casing co-ordinating the tubular cap with the piston member aforesaid,
- 30 whereby both the local and distant valves are concurrently actuated by the closet seat to effect flushing of the closet bowl, and an inclined connection from the distant valve into the closet discharge for draining-off all water
- 35 intermediate said local and distant valves when the service supply is shut-off.
